UNITED STATES PATENT OFFICE.

OLE OLSEN AND HAGBART EVENSON, OF BELVIEW, MINNESOTA.

CORN-PLANTER.

SPECIFICATION forming part of Letters Patent No. 670,685, dated March 26, 1901.

Application filed June 11, 1900. Serial No. 19,860. (No model.)

To all whom it may concern:

Be it known that we, OLE OLSEN and HAGBART EVENSON, citizens of the United States, residing at Belview, in the county of Redwood and State of Minnesota, have invented certain new and useful Improvements in Corn-Planters; and we do hereby declare the following to be a full, clear, and exact description of the invention, such as will enable others skilled in the art to which it appertains to make and use the same.

Our invention has for its object to provide an improved corn-planter; and to this end it consists of the novel devices and combinations of devices hereinafter described, and defined in the claims.

The invention is illustrated in the accompanying drawings, wherein like characters indicate like parts throughout the several views. Figure 1 is a plan view of the improved machine, some parts being removed. Fig. 2 is a rear elevation of the machine. Fig. 3 is a side elevation of the same. Fig. 4 is a vertical section approximately on the line $x^4 x^4$ of Fig. 1. Fig. 5 is a detail, on an enlarged scale, in section on the line $x^5 x^5$ of Fig. 1. Fig. 6 is a similar view to Fig. 5, but in section on the line $x^6 x^6$ of Fig. 1, some parts being broken away. Fig. 7 is a horizontal section on the line $x^7 x^7$ of Fig. 5. Fig. 8 is a bottom plan view of one of the shoes. Fig. 9 is a plan view of one of the seed-magazines, the cover thereof being removed. Fig. 10 is a horizontal section approximately on the line $x^{10} x^{10}$ of Fig. 6, and Fig. 11 is a horizontal section taken approximately on the line $x^{11} x^{11}$ of Fig. 9.

The machine or wheel frame 1 is pivotally mounted by means of bearings 2 on a driving axle or shaft 3, on the ends of which the traction-wheels 4 are mounted, being preferably connected therewith by pawl and clutch driving devices. (Not shown, but of any ordinary construction.) The forwardly-projected portions or beams of the main frame 1 are pivotally connected by brackets 5 to the forward or intermediate portion of a transversely-extended supplemental or runner frame 6. The supplemental or runner frame 6 is provided with a pole 7, which is rigidly connected to the intermediate portion thereof, as best shown in Fig. 1.

The planting-shoes, to be hereinafter described, are mounted on or connected to the supplemental frame 6, and to raise and lower the said supplemental frame, together with the parts carried thereby, a lifting-lever 8 is pivoted, as shown, to the rearwardly-projected end of the pole 7 and to a lock-segment 9 by means of a pin or stud 10. The lifting-lever 8 is provided with a hand-operated latch 11 for co-operation with the lock-segment 9, and the lower end of the said lever is pivotally connected to the main frame 1, as shown, by a link and eye 12. (See particularly Figs. 1 and 4.) As the outer end of the pole will be supported by the draft-animals when the machine is in operation, it is evident that the supplemental frame may be raised and lowered and held in different vertical positions by means of the latch-levers 8 11 and lock-segment 9.

The driver's seat 13 is shown as supported from the rear portion of the main frame 1. To keep the peripheries of the traction-wheels 75 clean, scrapers 14 on a common shaft 15, mounted in the main frame 1, are provided. A spring 16, connected at one end to the main frame 1 and at its other end to a short arm 17 of the shaft 15, normally holds the scrapers 14 in contact with the wheels 4. Another arm 18 on the shaft 15 is connected by a link 19 to a foot-lever 20, pivoted at 21 to one side of the main frame, with its upper end in position to be engaged by the foot of the driver seated on the seat 13. By pressing on the upper end of the lever 20 with the foot the scrapers 14 may be thrown into inoperative positions.

The marking devices (one at each side of the machine) are connected one to each end of the supplemental frame 6, and as these parts, as well as the co-operating planting devices, are in duplicate they will be described in the singular. A long counter-shaft 22 is 95 mounted in suitable bearings in the supplemental frame 6, with its ends terminated approximately at the ends of the said frame 6. This shaft receives its motion from a sprocket-chain 23, which runs over a driven sprocket 24 on the said shaft 22 and over a driving sprocket 25 on the driving-axle 3. The driving-sprocket 25 is loose on the shaft 3 and is provided with a half-clutch 26, with which a

coöperating half-clutch 27, mounted to slide on but to rotate with the shaft 3, coöperates. A spring 28 puts the half-clutch 27 under strain to engage the half-clutch 26. The sliding half-clutch 27 is adapted to be moved and held in either an operative or an inoperative position by a latch-lever 29, pivoted to a latch-segment 30, which in turn is rigidly secured to the main frame 1.

10 Of the parts of each marking device the numeral 31 indicates an approximately V-shaped frame which is hinged at 32 to the adjacent end of the supplemental frame 6.

15 33 indicates a shaft journaled in the outer portion of the frame 31 and hinged to the adjacent end of the driven shaft 22 by a knuckle-joint 34, which is located in transverse line with the pivots 32 of the said frame 31, so as to permit said frame 31 to be raised 20 while the machine is in action. At its outer end the shaft 33 is provided with a wheel 35 and with a radially-projected marker 36.

25 To enable the operator from his seat to raise and lower the marking devices, or either 30 of them, at will, a latch-lever 37 and coöperating latch-segment 38 is provided at each side of the machine, and each lever is connected by a cord or flexible connection 39 to the outer end of the coöperating frame 31. 35 The cord 39 is passed over a guide-sheave 40 on the main frame 1 and over a guide-sheave 42 on the upper end of an arm 43, pivoted to the supplemental frame 6 at 44. The outward movement of the arm 43 is limited by 40 the stop 45 on the supplemental frame. For a purpose to be hereinafter noted the lever 43 will be moved inward when the frame 33 is raised, and to accomplish this a cord or connection 39 is provided with a stop 46, which when the frame 33 is raised, as shown 45 at the left in Fig. 2, positively forces the said arm 43 inward.

45 A planting-shoe with coöperating planting mechanism is, as already indicated, located at each side of the machine. Such planting-shoe 47 works just outside of the traction-wheel at that side of the machine and is pivoted to the forward portion of the supplemental frame 6, as shown at 48. The rear 50 portion of the shoe 47 is divided or flanged and provided with a transversely-extended spacing-block 49 and with a hollow vertically-extended feed leg or spout 50, the lower end of which opens at or just above the inclined 55 rear portion of the block 49. A cut-off blade or dropper 51 is pivoted between the rear flanges of the shoe 47 for coöperation with the block 49. A link 52 connects the upper portion of the blade 51 to the lower end of a trip-lever 53, which is pivoted between the sides of the shoe and is subject to a spring 54, connected thereto and to a drag-bar 55, one end of which is secured to the side of the shoe 47 and the other end of which is pivoted to the 60 supplemental frame 6, in line with the shoe-pivots 48. Preferably there are two bars 55 for each shoe, so arranged as to prevent un-

due lateral movements of the said shoe. The spring 54 tends to hold the cut-off blade 51 in its closed position, (indicated at Fig. 5,) 70 in which position it coöperates with the block 49 and the sides of the shoe to hold the kernels of corn dropped through the leg 50.

Just above the shoe 47 the shaft 22 is provided with a crank portion 56, one side of 75 which crank has a cam extension 57, for a purpose to be hereinafter noted. Working on the crank portion 56 is a box or bearing 58, which is mounted to slide between the prongs of a bifurcated link 59, the lower end 80 of which is pivoted between the sides of the shoe 47. A spring 60 is compressed between the box 58 and the lower end of the link 59, tending to force the box upward, or, rather, the link downward. A pin 61, passed through 85 the upper ends of the prong of the link 59, limits the downward movement of said link, and hence of said shoe 47.

The shoe above described is normally carried above the ground; but at each hill to be 90 planted it is forced downward and into the ground by the movement of the crank 56. While the shoe is forced into the ground, as shown in Fig. 6, the cam projection 57 strikes the upper end of the trip-arm 53, and through 95 the connection 52 moves the cut-off blade 51 into its open position, (indicated in Fig. 6,) and thus drops the corn previously held thereby, as shown in Fig. 5.

Secured by a shelf or bracket 62 on the supplemental frame 6, immediately over the coöperating shoe 47, is a seed magazine or receptacle 63, provided with a disk or rotary bottom 64 and preferably, also, with a lid 65. The rotary bottom has a plurality of perforations 66, which are adapted to be brought successively into registration with a perforation 67 in the bottom of the shelf 62, immediately above the upper end of the shoe-leg 50. As shown, a sleeve 68, secured to the 100 bottom of the shelf 62, surrounds the said perforation 67 and is adapted to telescope into said shoe-leg 50 when the shoe is raised, as shown in Fig. 5. The seed-magazine 63 is provided with an inwardly-projecting segmental section 69, formed with an upwardly-bulged channel 70, which overlies the particular perforation 66 of the bottom 64, that stands in registration with or in the vicinity of the perforation 67. Within the raised 105 portion 70 is a spring-cam or cut-off 71, which directs the kernels of corn which may project from the perforation or pocket 66 downward through the line-perforations 66 67. In the construction illustrated the magazine 63 115 is supported from the shelf 62 by a plurality of legs or brackets 72, and the rotary bottom 64 is journaled on a short thimble 73, held between said shelf and the segmental section 69 by a short nutted bolt 74.

The rotary bottom 64 is provided with peripheral notches 75, corresponding in number to the number of perforations or seed-pockets 66. A spring-retaining pawl 76 on the

shelf 62 engages in succession said notches 75 to temporarily hold the rotary bottom with one or the other of its perforations or pockets 66 alined with the perforations 67 in the shelf 62.

A step-by-step movement is given to the rotary bottom under the advance movement of the machine from a segmental gear 77, secured on the driven shaft 22. The segmental gear 77 engages intermittently with an intermediate gear 78, suitably journaled on one of the depending sides of the shelf 62, as best shown in Fig. 5. This gear 78 meshes with gear-teeth 79 on the under peripheral portion 15 of the rotary bottom 64. The segmental gear 77 has only enough teeth to cause by its passing engagement with the intermediate gear 78 the rotary bottom 64 to move the angular distance between its perforations or pockets 20 66, and this movement is arranged to take place while the shoe 47 and leg 50 are raised, as shown in Fig. 5, at which time the kernels of corn required for one hill are dropped through the leg 50 onto the block 49 and cut-off blade 51, from whence, as already stated, 25 they will be deposited in the ground while the said shoe is forced downward, as indicated in Fig. 6.

The action of the marking device or check-row marker will be readily understood by all persons familiar with this class of mechanism. It is, however, evident that the marker on but one side of the machine will be used at one time. Hence that mechanism on the 35 inoperative side of the machine should be elevated and remain idle.

The outer ends of the shaft 22 instead of being rigid are loosely connected, as shown at 80 in Fig. 2, the sections being connected 40 by half-clutches 81 82, mounted to rotate with their respective sections and the former to slide on the loose outer section 22^a to and from engagement with the coöperating half-clutch 82. A spring 83 tends to hold the half-clutch 81 in engagement with the half-clutch 82; but the said half-clutch 82 is adapted to be moved into an inoperative position by the oscillation of a rock-shaft or rod 84, mounted in suitable bearings 85 on the supplemental 45 frame 6 and provided with a semicircular depending crank-section 86, as shown in Figs. 1 and 2, which engages a groove 87 in the said half-clutch 81. The above releasing movement of the rock-shaft 84 is automatically produced when the marking-wheel is raised, as indicated in Fig. 2 and as already described, by the engagement of the arm 43 with a vertical projection 88 at the rear end of the said rock-shaft 84. The action of the 50 machine as a check-row planter should be understood from the foregoing description. The machine is, however, capable of use for planting fodder-corn, in which case the corn should be planted in rows having very closely-spaced hills. For this latter operation a supplemental segment 89 is applied to the segmental gear 77, as indicated by dotted lines 55

in Fig. 5. As shown, this supplemental gear-section 89 has two groups of teeth, which, with the teeth of the gear 77, make a gear having 70 three groups of teeth adapted to move the rotary bottom of the seed-magazine three steps of movement for each rotation of the shaft 22. In this action the link 59 should be rendered inoperative, which may be done by disconnecting it from the crank 56 by removing the pin 61. Then by means of a brace 90 (indicated by dotted lines in Fig. 6) and applied between the shoes 47 and the down-turned sides of the shelf 62 the said shoe is 75 held downward, so that it will form a continuous furrow. Also by means of a pin 91, passed through the cut-off blade 51, back of the shoe 47, or by some other suitable device, the said blade 51 is held open against the action of its spring 54, as indicated in Fig. 6. These adjustments having been effected, the machine is adapted for planting fodder-corn.

What we claim, and desire to secure by Letters Patent of the United States, is as follows: 90

1. In a planter, the combination with a runner-like shoe pivoted at its forward end, of mechanism operated by the traction wheel or wheels for intermittently forcing the rear portion of said shoe into the ground, under the 95 advance movement of the machine, substantially as described.

2. In a planter, the combination with a runner-like shoe and mechanism operated by the traction wheel or wheels for moving said shoe 100 intermittently into and out of contact with the ground, of intermittent seed-dropping mechanism, a leg or spout receiving therefrom and carried by said shoe, and a pivoted cut-off blade or dropper coöperating with said shoe below said spout to intermittently drop the seed, and mechanism actuated from the traction-wheel for opening and closing said cut-off blade or dropper, substantially as described. 105

3. In a planter, the combination with a runner-like shoe pivoted at its forward end and movable into and out of the ground under the advance movement of the machine, of a pivoted spring-held dropping device or cut-off 115 and a rotary cam operating said cut-off intermittently and while said shoe is forced into the ground, substantially as described.

4. In a planter, the combination with a seed-magazine and intermittent feeding device, of a shoe pivoted at its forward end, a crank-shaft with a spring connection to the rear portion of said shoe for intermittently forcing the same into and out of the ground, and means for driving said crank-shaft under the advance movement of the machine, substantially as described. 120

5. In a planter, the combination with an intermittently-movable shoe pivoted at its forward end and mounted for movement into and out of contact with the ground, of a crank and pitman connection for raising and lowering said shoe, and a seed-dropping device 130 carried by said shoe coöperating with a part

of said shoe to hold and drop the seed and operated by the movement of said crank-shaft while said shoe is forced into the ground, substantially as described.

5 6. In a planter, the combination with the shoe 47 pivoted at its forward end, of the crank-shaft with spring pitman connection 58, 59, 60, to said shoe, the leg 50 delivering the seeds to said shoe, the dropper or cut-off 10 blade 51 pivoted to said shoe, and co-operating with the block 49 below said leg 50, and means for intermittently operating said cut-off blade 51 comprising the spring-held lever 53 connected to said blade 51, and a cam projection 15 57 carried by said crank-shaft and operating on said lever 53, substantially as described.

7. In a planter, the combination with a seed-magazine, having a perforated rotary bottom, a shoe engageable with the ground, co-operating devices for delivering the seeds from the perforations of said rotary magazine-bottom, and means for intermittently rotating said bottom, comprising a segmental driving-gear and an intermediate gear operating 20 25

upon the said rotary bottom, said segmental gear having a detachable supplemental section for completing it, substantially as described.

8. In a planter the combination with planting mechanism, of a marking device the shaft of which is driven from the traction-wheels, a knuckle-joint interposed in said shaft, the hinged frame section or brace hinged to the main frame in axial line with said knuckle-joint and serving to hold the said shaft against movements in horizontal plane, and a flexible connection extending from said pivoted frame section or brace and to an operating-lever on the frame of the machine, and an intermediate guide for said flexible connection located above said knuckle-joint substantially as described. 30 35 40

In testimony whereof we affix our signatures in presence of two witnesses.

OLE OLSEN.

HAGBART EVENSON.
